UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

FEEDING MECHANISM FOR SEWING-MACHINES.

1,192,608.

Specification of Letters Patent. Patented July 25, 1916.

Original application filed September 6, 1912, Serial No. 718,807. Patent No. 1,164,789, dated December 21, 1915. Divided and this application filed November 10, 1913. Serial No. 800,037.

To all whom it may concern:

Be it known that I, ALBERT H. DE VOE, a citizen of the United States, residing at Westfield, in the county of Union and State 5 of New Jersey, have invented certain new and useful Improvements in Feeding Mechanisms for Sewing-Machines, of which the following is a specification, reference being had therein to the accompanying drawings.

10 This invention has for its primary object to provide a sewing machine with feeding mechanism and with automatically acting controlling means therefor whereby the work is advanced by groups of feeding 15 movements, the feeding movements of each group differing from those of the adjacent groups.

The invention is adapted especially for use in connection with the stitch-forming 20 and cord-guiding mechanism forming the subject of my Patent No. 1,164,789, dated December 21, 1915, of which the present application is a division.

In the aforesaid pending application 25 means are provided for applying to one of the flaps of a Japanese shoe or "tabi"-upper a cord which is doubled at the upper edge of the flap and led downwardly in two parallel branches. Each branch of the cord is 30 fastened to the flap by spaced groups of tacking-stitches connected by series of straight-away stitches. Thus between each group of tacking-stitches a cord-loop is formed, said loop being adapted to receive 35 a flat metallic fastener secured to the face of the other tabi flap.

In forming the tacking-stitches which 40 secure the cord to the tabi flap it is desirable to mass the same at the points which receive the greatest strain in use. And to this end the feeding mechanism of the present invention is adapted to impart a continuous slow advancing movement to the work during the formation of the tacking-stitches 45 which secure the cord at the upper edge of the tabi flap, and said mechanism is also adapted to feed the work in such manner that in the subsequent spaced groups of tacking-stitches a few stitches are massed 50 at the ends of each cord-loop.

In its preferred embodiment the present improvement comprises a feed-dog and feed-lifting and feed-reciprocating eccentric therefor. A controlling cam is employed to

vary the action of the feed-reciprocating 55 eccentric and, periodically, to render said eccentric ineffective during the continuous advance of the feed-dog by means actuated by said controlling cam, during which periods the feed-dog is maintained in raised position and the feed-lifting eccentric is rendered ineffective. At the completion of a predetermined number of tack-forming cycles the controlling cam is adapted to be automatically uncoupled from its driving 65 means.

The invention will be understood in its details of construction by reference to the accompanying drawings, in which—

Figure 1 is a front side-elevation of a two- 70 needle sewing machine embodying the present improvements. Fig. 2 is a plan view of the under side of the same. Fig. 3 is a perspective view of the component parts of the feeding mechanism. Fig. 4 is a view of 75 the parts shown in Fig. 3 from the under side thereof, and Fig. 5 is a perspective view, partly in section, of the controlling cam and the releasing means therefor. Fig. 6 is a face view of a portion of a tabi-flap 80 showing cord-loops secured thereto in accordance with the present invention.

The invention is shown applied to a sewing machine constructed with the bed-plate A, hollow standard B, and overhanging 85 tubular arm D in which is journaled the main shaft 1 carrying at its rearward end the balance-wheel 2 with belt-pulley 3.

Journaled in the head of the overhanging arm, is a tubular needle-bar 4 on the lower 90 end of which is secured the needle-clamp 5 carrying the jogging needle 6. The main-shaft is provided with the usual quartering cranks 7 embraced by straps at the upper ends of the pitmen 8 whose lower ends are 95 similarly provided with straps embracing the quartering cranks 9 of the lower shaft 10, provided with the feed-actuating eccentric 11. Upon the upper side of the eccentric 11 rests the flat operative face 12 of a 100 lateral arm 13 fixed upon the rocking sleeve 14 which is journaled upon the rock-shaft 15, mounted in the bearing members 16 depending from the bed-plate. The rock-shaft 15 has fixed upon its rearward end the de- 105 pending and laterally extending arm 17 having a wearing face 18 adapted for engagement with the opposite side of the cam 11

from the arm 13. The arms 13 and 17 are normally pressed together by means of a spring 19 embracing the sleeve 14 and having one extremity secured to a collar 20 fixed upon said sleeve and the other end attached to a collar 21 secured upon the rock-shaft 15.

The arm 17 is shown provided in its rearward face with a segmental channel 22 in which is fitted the slide block 23 having pivotally connected therewith one end of a bent link 24 whose apertured opposite end is connected by means of the screw-pin 25 with the upwardly extending arm 26 secured upon the feed rock-shaft 27. The sliding connection between the arm 17 and the link 24 is shifted toward and from the rock-shaft 15 by means of a link 29 pivotally connected by the pin 29' to the link 24 at its lower end and attached at its upper end to the lateral arm 30 of the feed-regulator rock-shaft 31 journaled in and transversely of the standard B and having fixed to its rearward end the finger-lever 32. In its forward end the feed rock-shaft 27 has secured thereon the crank arm 33 carrying the stud-screw 34 which enters the apertured extremity of the feed-bar 35 to which is secured the usual feed-dog 36. The opposite end of the feed-bar is formed with the fork 37 which is in practice entered by a slide block 38 carried by the lateral arm 39 upon the forward end of the feed-lifting rock-shaft 40 to whose rearward end is secured the hub 41' of a laterally extending arm 41 adapted to rest upon the feed-lifting eccentric 42 fixed upon the lower shaft 10. The hub 41' is provided in its top at one side of the rock-shaft 40 with a socket between the bottom of which and the under side of the bed-plate A is inserted a spring 43 which normally presses the arm 41 downwardly into operative relation with the lifting cam 42. The feed-actuating arm 17 is formed at its outer extremity with a lateral seat 17' to which is secured by means of the screw 44 the base of an arm 45 formed with a transverse socket 46 in which is journaled the slide pin 47 carrying at its outer end the roller-stud 48. The enlarged rearward end or head of the pin 47 is pressed backwardly by means of a spring 49 interposed between the same and the inner end of the socket, so as to maintain the roller-stud 48 normally retracted into operative relation with an outer cam-track 70 formed upon the lower face of a cam-wheel C which, as hereinafter described, is adapted to control the feeding movements of the feed-dog 36.

Secured upon the lower shaft 10 is a worm 51 meshing with the worm-wheel 52 which is shown formed integral with the sleeve 53 journaled upon the tubular bearing stud 54 formed with a collar 55 secured in fixed position to the lower face of the bed-plate by means of screws 56. The sleeve 53 is pro-

vided with the coupling disk 57 formed with an annular series of uniformly spaced apertures 58. Within the tubular bearing stud is journaled the tubular hub 59 of a disk 60 formed in its lower face with a radial channel 61 within which is fitted the rigid arm 62 secured to the shouldered lower end of the coupling rod 63 to which it is fastened by means of the nut 64.

The rod 63 is extended upwardly through the hub 59 of the disk 60 and has fixed upon its upper end above the bed-plate the thrust-collar 65. The arm 62 has extending from its upper face the coupling stud 66 whose reduced upper portion 67 is adapted to enter one of the apertures 58 of the disk 57 but which is normally disengaged from such disk by the action of a spring 68 interposed between the top of the arm 62 and the upper end of a socket formed therefor around the rod 63 in the hub 59 of the disk 60.

Tapped into threaded apertures in the lower face of the annular flange 50 of the cam-wheel C are the screws 69 which secure the cam-wheel to the upper face of the disk 60.

The roller stud 48 carried by the feed-actuating arm 17 is adapted to engage the cam-tracks 70 and 71 of the cam-wheel C which serve to move the feed-actuating arm 17 toward and from the eccentric 11 and thus to control the normally effective action of the latter with respect to the feed-dog. The cam-track 70 acts in opposition to the spring 19 to permit the engagement of the arm 17 with the actuating cam 11 only at the high point of the cam, and the cam-track 71 wholly prevents such engagement, while serving by its inclination to cause a slight continuous movement of the arm 17 from the cam-track 71 against the action of the spring 19. As will be observed the spring 19 serves to normally draw together the arms 13 and 17 of the yielding yoke so as to lightly embrace the eccentric 11, the spacing apart of the wearing faces 12 and 18 being determined by the adjusting screw carried by the tail of the arm 13 and whose point rests against the extension of the arm 17, as represented in Fig. 3.

As shown more particularly in Figs. 2 and 4 of the drawings, segmental gap 72 is formed in one side of the cam-wheel to afford clearance for the roller-stud 48 so as to permit the free vibration of the arm 45 under the action of the eccentric 11 upon the arm 17 during a portion of the rotation of the cam-wheel thereby imparting to the feed-dog a group of feeding movements, each corresponding to the full throw of the feed-actuating eccentric. A portion of the outer cam-track 70 is also cut away to form a recess for the reception of the adjustable channeled section 73 which is secured to the cam-wheel by means of fastening screws 74, 130

passing through inclined slots in the section 73. By loosening the screws 74, the section 73 may be shifted upwardly or downwardly in its recess, so as to change its controlling 5 position relative to the roller-stud 48.

Suitably journaled beneath the bed-plate is an endwise movable stop-rod 76 whose forward end extends, in the initial position of the parts, beneath the lower edge of the 10 striking-plate 77, secured by screws 78 upon the feed-lifting arm 41, as represented in Fig. 3, so as to maintain the feed-dog in elevated position and out of the range of movement of the lifting cam 42 while the roller-stud 48 performs its slow and continuous 15 work-advancing movement under the control of the cam-track 71. The rod 76 has fixed thereon the hub 79 of a depending arm 80 having a flat operative forward face 20 adapted to contact with the head of the pin 47 to shift the roller-stud 48 forwardly under the action of a spring 81 surrounding the rod 76 and interposed between the hub 79 and a bearing member of the bed-plate. 25 Fixed upon the rod 76 and extending upwardly through a slot formed in the bed-plate is a stud 82 to the upper end of which is rigidly secured the segmental arm 83 carrying the roller-stud 84 adapted for engagement with the peripheral projection 85 of a cam disk 86 fixed upon the upper end 30 of the tubular hub 59 of the coupling disk 60.

The arm 83 is provided adjacent the 35 roller-stud 84 with a forwardly projecting finger-piece 87 and at the opposite end with a tooth 88 adapted for engagement with a detaining shoulder afforded by the collar 89 upon the lateral arm 90 of a latch-lever fulcrumed upon the push-rod 91, the latter being journaled in the bracket piece 92 secured to the standard B and extending downwardly through an aperture in the bed-plate A. The latch-lever is formed with a rearwardly extending arm 93 carrying the tripping-pin 94 and is normally pressed to bring the arm 90 into latching relation with the arm 83 by means of a spring 95 interposed between the same and the base of the standard B. The hub of the latch-lever rests upon the top of the bed-plate in contact with which it is maintained by means of a rod 96 secured in the lug 97 of the latch-lever and having its upper end extended beneath the bracket-piece 92.

To the push-rod 91 below the bracket piece 92 is secured by means of the set-screw 98 the hub 99 of a plural-armed member comprising the coupling-controlling arm 100 having secured upon a seat in its outer end the wearing plate 101 adapted for introduction beneath the thrust-collar 65 of the coupling-rod 63. Extending rearwardly from the hub 99 is an arm 102 having a fork 103 in its extremity which embraces a trip-

ping-rod 104 mounted in the bearing member 105' formed upon an arm 105 provided with a collar 106 secured upon rack-bar 107 which is journaled in a suitable bearing member supported by the bed-plate A and 70 surrounded by a spring acting normally to press the bar into extreme forward position. Formed in the front side of the bar 107 is a series of ratchet teeth 108 (Fig. 5) extending forwardly over which is a pawl-retracting flange 109. In normal engagement with the ratchet-teeth 108 is the holding-pawl 110, fulcrumed upon a screw-pin 111 tapped into the bed-plate, and actuating pawl 112, fulcrumed upon the screw-pin 113 on the 80 reduced forward end of the rearwardly extending arm 114 of a rock-lever, the latter being mounted upon the fulcrum-stud 115 tapped into the bed-plate and having a forwardly extending arm formed with a yoke 85 117 which embraces an eccentric 118 fixed upon the tubular hub 59 of the coupling disk 60. The tail of the pawl 112 is formed in its rearward edge with a socket to receive a spring 119 resting against the adjacent 90 edge of the holding-pawl 110 whereby both pawls are maintained normally in operative relation with the ratchet-teeth 108. As will be observed, for each rotation of the controlling cam-wheel C the rock-lever 114 117 95 receives one rocking movement, and the counting bar 107 receives a step backwardly carrying with it the tripping-rod 104. This rod is provided with a transverse tripping-pin 120 which also receives step-by-step 100 movements toward the forked extremity 103 of the tripping-arm 102, and at the end of a predetermined number of rotations of the controlling cam engages the forked extremity of said arm, thereby shifting the 105 arm 100 in opposition to the spring 121 whose opposite ends are attached respectively to the collar 122, fixed to the push-rod 91, and the bracket piece 92, thereby retracting the contact-plate 101 from beneath the thrust-collar 65 and permitting the coupling-rod 63 to descend by the action of its spring 68, thus uncoupling the controlling cam from the continuously driven disk 57. As the spring 121 is substantially 110 stronger than the spring 68, it will be seen that the former acts to maintain the push-rod in raised position with its stop-collar 91 in engagement with the under side of the bracket piece 92 and the spring 68 compressed to hold the coupling stud 66 in operative engagement with the disk 57.

The overhanging arm D sustains the usual fulcrum-stud upon which is mounted the presser-bar lifting rock-lever 123 to the rearward end of which is connected by means of the screw-pin 124 the apertured head 125 of the treadle-rod 126 passing through the usual aperture in the bed-plate beneath which it is formed with the hooked ex- 130

5 extremity 127 to receive the upper end of the chain 128 whose opposite end is in practice connected with an actuating treadle. The treadle-rod has secured thereon near its 10 upper end the hub 129 of a laterally extending rigid arm 130 extending above the top of the push-rod 91, and it is also provided slightly above the bed-plate with a fixed collar 131 having in its lower face an inclined cam face adapted for engagement with the tripping finger 94 of the latch-lever, as shown in Fig. 5.

15 In order to set the machine for a tacking and stitching operation, the treadle-rod 126 is drawn down to lift the presser-foot above the throat-plate E for introduction of the work, which causes the engagement of the collar 131 with the tripping finger 94, thus 20 disengaging the collar 89 from the tooth 88 of the arm 83 which causes the stop-rod 76 to advance under the action of its spring to bring its forward extremity beneath the member 77 of the feed-lifting bar 41 and simultaneously press the pin 47 forwardly 25 to shift the roller-stud beneath the upper portion of the inclined cam-track 71. At the same time, the depression of the tripping-rod 104 under the action of the fork 103 causes the rocking of the counting-bar 30 107 wherein the flange 109 engages the pins upon the holding and actuating pawls 110 and 112 to forcibly retract the latter from the ratchet-teeth 108 thereby permitting the counting bar 107 to move into extreme forward initial position under the action of its 35 spring. The depression of the arm 100 with the push-rod 91 causes the descent of the wearing-plate 101 from the side of the thrust-collar 65 to a point below the latter, 40 beneath which it is caused to move by the torsional action of the spring 121, and the release of the treadle-rod 126 thereafter permits the push-rod 91 to rise under the action of the spring 121 and with it to rock the 45 counting-bar 107 into initial position and to lift the coupling-rod 63 for coupling the disk 60 and the attached cam-wheel C with the coupling-disk 57.

50 The setting of the machine in operation causes the cam-track 71 to slowly and continuously move arm 17 from feed actuating eccentric 11, thereby imparting a slow work-feeding movement to the feed-dog 36, the latter being maintained in raised position 55 by the stop-rod 76. Such movement of the feed-dog permits the stitching mechanism, fully described in my aforesaid Patent No. 1,164,789 dated December 21, 1915, to produce an initial group of massed tacking 60 stitches *a* (Fig. 6), to secure the cord to the upper edge of the tabi flap T.

Just as the roller-stud 48 reaches the end of the cam-track 71 and enters the clearance space 72, the nose or projection 85 of the cam 86 engages the roller-stud 84 of the

arm 83 and thereby retracts the stop-rod 76 to disengage it from the feed-lifting arm 41, simultaneously retracting the arm 80 to enable the roller-stud 48 to retract into the range of action of the cam-track 70. The 70 arm 83 being held in retracted position by engagement with the latch-lever arm 90, the stitching proceeds with the feed-actuating arm 17 in full engagement with the eccentric 11 thereby permitting the production of the 75 straightaway stitches *b* extending along the inner sides of the cord.

80 At the beginning of the second rotation of the controlling cam, the cam-track 70 acts upon the roller-stud 48 as a stop to reduce 85 the normal throw of arm 17, thereby shortening the feed-stroke to permit the production of the first few stitches of the second tack, said stitches, *c*, being closely associated, but somewhat more widely spaced 90 than those of the first tack. The encounter of the stud 48 with the adjustable cam-track section 73 now permits a somewhat greater amplitude of movement of the arm 17 whereby the spacing of a second series of stitches *d* in the tack is somewhat increased, while the presentation of the final section of cam-track 70 similar to the first causes the production of a third series of closely associated 95 stitches in the said tack similar to those first formed, after which a series of straightaway stitches is formed under the conditions previously described.

100 The groups of feeding movements for the tacking and straightaway stitches last described are repeated a number of times for 105 which the counting device is adjusted. As before explained, the shifting of the arm 102 causes the lateral movement of the arm 100 to disengage the wearing-plate 101 from the 110 thrust-collar 65 thereby permitting the coupling-rod 103 to descend under the action of its spring 68 for uncoupling the controlling cam C from the coupling disk 57. As this uncoupling takes place while the stop-rod 76 is retracted and the roller-stud 48 is in register with the clearance gap 72 of the cam C, it will be seen that the continued 115 operation of the machine will now produce an indefinite succession of parallel straightaway stitches, the stitch-forming and feeding mechanism acting under such conditions precisely the same as in any ordinary straightaway stitching machine.

120 It will be observed that the adjustment 125 upward or downward of the cam-track section 73 will effect a lengthening or shortening of each of the groups of feeding movements after the first, by increasing or decreasing the length of the intermediate feeding movements of each group. It is also evident that in case it is desired to produce a succession of tacks composed of massed tacking stitches, the manual shifting of the latch-lever by means of its finger piece dur- 130

ing the production of straightaway stitching succeeding an initial tack will permit the stop-rod 76 to reassume initial position so as to restore the controlling mechanism to starting condition but without affecting the timing of the disengagement of the controlling cam under the action of the counting device.

It is obvious that the shifting of the feed-regulator lever 32 will cause the shifting of the slide block 23 toward or from the rock-shaft 15, thereby varying the length of the feeding movements for the straightaway stitches and the consequent spacing apart of the consecutive tacking groups.

While the controlling-cam driving element 57 is shown provided with worm-driven means for turning it continuously in the same direction, it is evident that any other suitable means may be used for imparting movement thereto. The roller-stud 48 constitutes a normally operative cam follower which serves to restrict in greater or less degree, in conjunction with the cam-track 70, the maximum work-advancing action of the feeding mechanism and which, in conjunction with cam-track 71, serves to impart work-advancing movements to the feed-dog independently of the normally operative actuating means therefor. It is obvious that the mechanism employed to this end may be widely varied within the scope of the present invention.

Having thus set forth the nature of the invention, what I claim herein is:

1. In a sewing machine, the combination with stitch-forming mechanism, of feeding mechanism comprising a feed-dog, successively and independently acting means for moving the feed-dog in the same direction, and automatically acting means for controlling the successive action of said feed actuating means.

2. In a sewing machine, the combination with stitch-forming mechanism, of feeding mechanism comprising a feed-dog, means whereby said feed-dog is confined against lateral movement, a first actuating means for causing said feed-dog to feed the work during a series of stitch-forming cycles, a second actuating means for causing said feed-dog to feed the work during another series of stitch-forming cycles, connections between said feed-dog and said first and second actuating means and automatically acting controlling means for rendering said actuating means successively active.

3. In a sewing machine, the combination with stitch-forming mechanism, of feeding mechanism comprising a feed-dog, and means whereby the feed-dog is maintained in engagement with the work throughout a succession of stitch-forming cycles and moved in the same direction in consecutive cycles, and is given a plurality of rising and

falling and reciprocatory feeding movements in another succession of stitch-forming cycles.

4. In a sewing machine, the combination with stitch-forming mechanism, of feeding mechanism comprising a feed-dog, and means whereby the feed-dog is maintained in operative relation with the work and moved continuously in the same direction to advance the work during one succession of stitch-forming cycles and is given a plurality of rising and falling and reciprocatory feeding movements in another succession of stitch-forming cycles.

5. In a sewing machine, the combination with stitch-forming mechanism, and feeding mechanism comprising a feed-dog and normally acting lifting and reciprocating means therefor for advancing the work for each stitch-forming cycle, of means for causing the feed-dog to remain elevated and to move in the same direction in consecutive cycles of a series of stitch-forming cycles.

6. In a sewing machine, the combination with stitch-forming mechanism, and feeding mechanism comprising a feed-dog, feed-lifting and reciprocating cams and members connected with the said feed-dog and normally maintained within the range of action of said cams, of automatically acting means whereby said feed-dog lifting and reciprocating cams are rendered ineffective during the production of a succession of stitches and are permitted to thereafter perform their functions in the actuation of the feed-dog.

7. In a sewing machine, the combination with stitch-forming mechanism, and feeding mechanism comprising a feed-dog, feed-lifting and reciprocating cams and members connected with the said feed-dog and normally maintained within the range of action of said cams, of automatically acting means for varying the effective action of the feed-dog reciprocating cam upon the feed-dog in advancing the work in the production of successive groups of stitches, and controlling means whereby said feed-dog lifting and reciprocating cams may be rendered ineffective in the production of a succession of stitches and are permitted to thereafter perform their functions in the actuation of the feed-dog.

8. In a sewing machine, the combination with stitch-forming mechanism, and feeding mechanism comprising a feed-dog feed-lifting and reciprocating cams and members connected with the said feed-dog and normally maintained within the range of action of said cams, of automatically acting means for varying the effective action of the feed-dog reciprocating cam upon the feed-dog in advancing the work in the production of successive groups of stitches, controlling means whereby said feed-dog lifting and re-

ciprocating cams may be rendered ineffective in the production of a succession of stitches and are permitted to thereafter perform their functions in the actuation of the feed-dog, and means for rendering said controlling means ineffective.

9. In a sewing machine, the combination with stitch-forming mechanism, and feeding mechanism comprising a feed-dog, feed-lifting and reciprocating cams and spring-pressed members connected with the said feed-dog and normally maintained within the range of action of said cams, of a stop-member adapted to be thrown into and out of the range of movement of one of said members to maintain the feed-dog lifted for a succession of stitch-forming cycles, and means independent of the feed-dog reciprocating cam for imparting to the feed-dog during said succession of stitch-forming cycles progressive movement in the same direction.

10. In a sewing machine, the combination with stitch-forming mechanism, and feeding mechanism comprising a feed-dog, feed-lifting and reciprocating cams and spring-pressed members connected with the said feed-dog and normally maintained within the range of action of said cams, of a stop member adapted to be thrown into and out of the range of movement of one of said members to maintain the feed-dog lifted for a succession of stitch-forming cycles, and means for rendering said feed-dog reciprocating cam ineffective and for moving the feed-dog in the same direction in consecutive cycles.

11. In a sewing machine, the combination with stitch-forming mechanism, of feeding mechanism comprising a feed-dog, an actuating cam, a yoke constructed with relatively yielding members embracing said cam, an operative connection between one of said members and the feed-dog, and variably acting means for limiting the movement of the last-named yoke member under the action of said cam.

12. In a sewing machine, the combination with stitch-forming mechanisms, of feeding mechanism comprising a feed-dog, an actuating cam, a yoke constructed with relatively yielding members embracing said cam, an operative connection between one of said members and the feed-dog, and means including a stop member formed with a plurality of differently acting portions adapted for successive presentation to an element of said operative connection, whereby the length of throw of the feed-dog is varied.

13. In a sewing machine, the combination with stitch-forming and feeding mechanism including work-engaging means and means operating to impart work-feeding movements thereto, of feed-controlling means comprising a movable cam member pro-

vided with a plurality of operative portions, and a spring-pressed follower adapted for successive engagement with said operative portions of the cam and having a connection with said feeding mechanism whereby the action of the latter is controlled.

14. In a sewing machine, the combination with stitch-forming mechanism, of feeding mechanism comprising a feed-dog, an actuating cam, a spring-pressed follower therefor, an operative connection between said follower and the feed-dog, a stud carried by an element of said operative connection, and a movable cam formed with a plurality of operative portions for engagement by said stud, one of which portions is adjustable relatively to the adjacent portion.

15. In a sewing machine, the combination with stitch-forming and feeding mechanism, of feed-controlling means comprising a rotary cam formed with a track in segmental portions of which the one is adjustable relatively to the other, and a spring-pressed follower adapted for successive engagement with said operative portions of the cam and having a connection with said feeding mechanism whereby the action of the latter is controlled.

16. In a sewing machine, the combination with stitch-forming mechanism, of feeding mechanism comprising a feed-dog, an actuating cam, a spring-pressed follower therefor, an operative connection between said follower and the feed-dog, a stud carried by an element of said operative connection, and a rotary cam formed with a track in segmental portions of which the one is adjustable relatively to the other, said portions being adapted for successive engagement by said stud.

17. In a sewing machine, the combination with stitch-forming and feeding mechanism, of feed-controlling means comprising a rotary cam provided with a plurality of concentric cam-tracks arranged side by side, a spring-pressed endwise movable stud adapted for engagement separately with each of said cam-tracks, and means for shifting said stud endwise.

18. In a sewing machine, the combination with stitch-forming mechanism, of feeding mechanism comprising a feed-dog, an actuating cam, a spring-pressed follower therefor, an operative connection between said follower and the feed-dog, a stud carried by and movably sustained upon an element of said operative connection, a movable cam provided with a plurality of cam-tracks arranged side-by-side and transversely of said stud with which they are adapted for engagement, and means for shifting said stud endwise to effect its alternate engagement with said cam-tracks.

19. In a sewing machine, the combina-

tion with stitch-forming mechanism, of feeding mechanism comprising a feed-dog, an actuating cam, a spring-pressed follower therefor, an operative connection between 5 said follower and the feed-dog, a stud carried by and movably sustained upon an element of said operative connection, a rotary cam provided with relatively inclined segmental cam-tracks, and means for shifting 10 said stud endwise to effect its alternate engagement with said cam-tracks.

20. In a sewing machine, the combination with stitch-forming mechanism, and feeding mechanism comprising a feed-dog, an actuating cam therefor, a spring-pressed follower for said cam, an operative connection 15 between said follower and the feed-dog, a stud carried by an element of said operative connection, and a rotary cam formed with a 20 segmental cam-track adapted for engagement with said stud to arrest its normal throw under the action of said cam and provided with an adjacent recess for clearance 25 for said stud whereby it is permitted to move freely under the action of said actuating cam.

21. In a sewing machine, the combination with stitch-forming mechanism, and feeding mechanism comprising a feed-dog, an actuating cam therefor, a spring-pressed follower for said cam, an operative connection 30 between said follower and the feed-dog, a stud carried by an element of said operative connection, and a rotary cam adapted for 35 engagement by said stud and formed with a segmental cam-track in adjacent sections, one of which is adjustable relatively to the other and with a clearance recess adjacent one of said sections.

40. 22. In a sewing machine, the combination with stitch-forming and feeding mechanism, of feed-controlling means comprising a rotary cam provided with a plurality of concentric segmental cam-tracks, and adjacent 45 clearance recess, a spring-pressed endwise movable stud adapted for engagement separately with each of said cam-tracks and for unrestricted movement within said clearance recess, and means for shifting said 50 stud endwise.

23. In a sewing machine, the combination with stitch-forming mechanism, of feeding mechanism comprising a feed-dog, an actu-

ating cam, a spring-pressed follower therefor, an operative connection between said 55 follower and the feed-dog, a stud carried by and movably sustained upon an element of said operative connection, a movable cam provided with a plurality of cam-tracks arranged side-by-side and transversely of said 60 stud with which they are adapted for engagement and with a clearance recess for said stud adjacent said cam-tracks, and means for shifting said stud endwise to effect its alternate engagement with said 65 cam-tracks.

24. In a sewing machine, the combination with stitch-forming mechanism, and feeding mechanism comprising a feed-dog, an actuating cam, and an operative connection 70 between said cam and feed-dog, of a rotary controlling cam adapted for operative connection with said feeding mechanism, a constantly moving driving element therefor, and releasable means for connecting said 75 controlling cam with its driving element for rotation in unison with the latter.

25. In a sewing machine, the combination with stitch-forming mechanism, of feeding- 80 mechanism comprising a work-engaging element, an actuating cam, a cam-follower, and connections between said cam-follower and said work-engaging element, of an automatically operating controlling cam, acting on said cam-follower to vary the limit of 85 movement thereof in one direction, thereby modifying the action of said actuating cam on said work-engaging element.

26. In a sewing machine, the combination with stitch-forming mechanism, feeding 90 mechanism comprising a feed-dog, an actuating cam rotating at a given speed, and operative connections including a cam-fol- 95 lower between said cam and said feed-dog, of a controlling cam, rotating at a slower speed and adapted to control the action of said first mentioned cam on the cam-fol- lower.

In testimony whereof I have signed my name to this specification in the presence of 100 two subscribing witnesses.

ALBERT H. DE VOE.
